UNITED STATES PATENT OFFICE

2,043,055

ADJUSTABLE NECKTIE

William Mayer, New York, N. Y.

Application August 23, 1935, Serial No. 37,438

5 Claims. (Cl. 2—155)

My present invention relates generally to neckwear, and has particular reference to an improved type of adjustable neckband.

It is a general object of my invention to provide an improved adjustable necktie, of the general character illustrated in United States Letters Patent No. 2,003,359, issued June 4, 1935. This type of necktie has a neckband portion which is adjustable in length by doubling it back upon itself and by providing at its end a male fastening element which is adapted to engage with a selected one of a series of openings or perforations in the neckband.

The more specific objects of the present invention include an improved mode of assembly of various elements, whereby the outward appearance of the necktie is more attractive; whereby the construction is more compact and easier to slip through or under a collar; and where the 20 adjustable feature is coupled with a maximum amount of strength and wearing qualities.

In accordance with my present invention, the neckband portion consists of inner and outer plies of tie material, which are often of relatively delicate fabric; and the perforations hereinbefore mentioned are provided in the inner ply. Where the male fastening element is in the form of a hook, this ply alone would be insufficient to withstand the stresses that are produced when the hook is engaged with a perforation. Accordingly, I provide a reinforcement strip of special character, and associated with the tie construction in a novel manner.

There are a number of reasons why a reinforcement strip should be positioned on the exterior surface of the neckband. Apart from other considerations, the strip affords a convenient means for applying suitable indicia adjacent to the perforations, the markings being relevant to the adjustabilities in effective neckband length afforded by the perforations, respectively.

I have found that a highly efficient construction can be produced at relatively small expense, with a minimum of labor and material, by providing the reinforcement strip with perforations registering with those in the inner ply, and by interengaging each pair of registering perforations marginally.

In one embodiment, the reinforcement strip is narrower than the neckband portion and is stitched along its edges to the outside surface of the inner ply, the stitches being disposed within the medial area lying between the relatively thicker margins of the neckband portion. In such a construction, the reinforcement strip is

selvaged along its longitudinal edges. By the term "selvage" I intend to refer to the type of selvage which is usually provided by weaving during the manufacture of the fabric, whereby the resultant product is of single-ply substantially uniform thickness throughout.

In another, and preferred, embodiment, the reinforcement strip is coextensive in width with that of the neckband portion and is secured in position by the same invisible stitching which holds the inner and outer plies of the tie together. These plies have their longitudinal edges turned inward, and the reinforcement strip has its longitudinal edges similarly turned inward, whereby a single series of concealed stitches holds all the elements in proper relationship.

In a construction of the present character, it is preferable, though not absolutely necessary, to provide a protective lining within the neckband portion at least coextensive in length with the perforated area of the neckband. This lining, with the outer ply, serves to conceal the fastening element from the outside by two thicknesses of material.

I achieve the foregoing objects, and such other objects as may hereinafter appear or be pointed out, in the manner illustratively exemplified in the accompanying drawing, wherein—

Figure 1 is a perspective view of a tie of the ready-made variety, embodying the features of the present invention;

Figure 2 is an enlarged cross-sectional view taken substantially along the line 2—2 of Figure 1;

Figure 3 is a perspective view showing the manner in which the present invention may be applied to the type of tie that is not ready-made;

Figure 4 is a perspective view showing the manner in which the invention is adapted to a four-in-hand type of tie; and

Figure 5 is a view similar to Figure 2, illustrating a modification.

The ready-made type of bow tie embodies the bow 10 and the preformed knot 11. Extending in opposite directions from the rear of the knot 11 are the neckband portions 12 and 13. The neckband of the tie is made adjustable in length by providing a male fastening element 14 (which I have illustratively shown in the form of a hook) at the extremity of the neckband portion 13, whereby this portion may be doubled back upon itself to engage the hook in any one of a series of perforations provided in a predetermined arrangement. A metallic loop 15 is mounted on the neckband portion 13 and is adapted to be

engaged at its midportion by a hook 16 that is carried at the extremity of the neckband portion 12.

The manner of applying the members 14 and 5 16 to the extremities of the neckband portions has not been illustrated in detail, because these particular portions of the structure have no bearing 10 upon the present invention.

The neckband portion 13 is composed of the 10 inner and outer plies of tie fabric 17 and 18. The longitudinal edge portions of these plies are turned inwardly and stitched together by the concealed stitching 19. As will be understood by those skilled in the art, this requires that the 15 plies 17 and 18 be first assembled back to back, and then, after stitching them together, the entire assembly is turned inside-out.

In accordance with my present invention, the 20 inner ply 17 is provided with a series of longitudinally spaced perforations which are arranged along a midportion of the ply at predetermined distances from one another, the location of these 25 perforations being such that the neckband as a whole may be adjusted to different neckband or collar sizes. In the present drawing I have chosen to illustrate the perforations in the form of circular openings, since such perforations are best adapted to receive a hook. It will be understood, however, that the perforations may, if 30 desired, be in the form of elongated slits, like buttonholes, whereby the male fastening element may partake of the nature of a button.

In carrying out the present invention, a reinforcement strip 20 of suitably strong and sufficiently 35 attractive fabric (but not configured or ornamented like the tie material itself) is secured to the outside surface of the inner ply 17. It embodies a series of perforations which register with the perforations in the ply 17, and each pair 40 of registering perforations is marginally interengaged, as shown illustratively by the stitching 21 in Figure 2.

In the embodiment of Figure 2, the strip 20 is 45 selvaged along its longitudinal edges 22, and it is narrower in width than the ply 17, so that it may be secured to the ply 17 by stitches 23 which are disposed entirely within the medial area between the relatively thicker margins of the neckband portion.

I have also illustrated the manner in which a protective lining 24 may be disposed between the plies 17 and 18, the longitudinal edges of this lining member being turned inwardly and engaged by the stitches 19.

The resultant perforations, exteriorly available 50 when the tie is used, are designated in Figures 1, 2, and 3 by the reference numeral 25.

In practice, a selected proper length of the strip 20 is first laid centrally upon the outer surface 60 of the ply 17. It is then stitched into position by means of stitches 23. The perforations 25 are then produced, either by hand or by machine, and the marginal edges of each pair of registering perforations are interengaged by suitable 65 means, e. g., the stitching 21. The ply 18 is then laid face down upon the outer side of the ply 17, and if a lining member is to be used it is also laid in proper superposed relation to these plies. The stitches 19 are then run to secure the several thicknesses together into a unitary assembly; and, finally, the entire assembly is turned inside-out, whereby a structure of the character illustrated in Figure 2 is produced.

One of the advantages of applying the strip 20 70 to the outside of the ply 17 lies in the fact that

suitable indicia 26 may be provided on the strip either before or after its assembly into the tie construction. Preferably, the strip 20 is manufactured in continuous lengths, and the markings 5 26 are produced thereon either by embroidery, stamping, or by the weave of the material itself. In the finished article, these indicia serve to designate the various adjustabilities in effective neckband length afforded by the perforations 25.

Figure 3 illustrates the manner in which the 10 invention is applied, with equal facility, to a tie that is not of the ready-made variety. No pre-formed knot is present in this construction, and the unperforated neckband portion is permanently secured, as at 27, to a metallic elongated 15 link through which the other neckband portion slidably extends. The extremity of the perforated neckband portion is provided with a male fastening element 28 which corresponds to the 20 element 14 of Figure 1.

In Figure 4, the invention is shown applied to a ready-made four-in-hand type of tie, and detailed description of this figure is not believed to be necessary, since it will be obvious that the features described in connection with Figures 1 25 and 2 are exactly the same in Figure 4, except for the fact that the knot 29 is a four-in-hand type of knot instead of a bow knot.

It will also be understood that the invention is applicable to a regular four-in-hand tie, the 30 tie in such a case being substantially identical with the tie illustrated in Figure 3, except that the ends are considerably longer and are shaped in the conventional four-in-hand manner.

In Figure 5, I have illustrated a modification 35 in which the extra stitches 23 of Figure 2 are unnecessary. For the sake of clearness, the reference numerals 17 and 18 are again applied to the inner and outer plies of tie material, and the reference numeral 24 is again applied to the lining member (where such member is employed). In this embodiment, the reinforcement strip 20' is coextensive in width with the neckband, and the longitudinal edges of the strip 20' are turned inwardly and are engaged by the concealed 45 stitches 19 which hold the assembly together. The openings 25 and the marginal means 21 for interengaging each pair of registering perforations are the same as in Figure 2.

The advantages of the present structure will 50 be obvious from the description given. The construction is sufficiently staunch, so that when a member such as the hook 14 or the hook 28 is inserted into a selected perforation, the stresses are not imparted solely to the tie material 17, but 55 are distributed between this ply and the reinforcement strip. Where a lining member is applied the fastening element, such as the hook mentioned, is concealed from the outside surface of the tie by two thicknesses of material constituted of the outer ply 18 and the lining member 24. The structure is compact and of lesser thickness at the center than at the margins. Thus, in Figure 2, there are four thicknesses of material along the midportion of the tie, while the margins are constituted of six thicknesses. In Figure 5, there are four thicknesses at the midportion and eight thicknesses at the margins. Where the lining member is omitted, the thicknesses at the midportions and at the margins are correspondingly reduced.

In the patent hereinbefore mentioned, an added strip of material is first stitched to a reinforcement band and then applied to the tie. I have found that in practice considerable care must be 75

taken to eliminate all loose and elongated threads or stitches, so that when this added assembly is attached to the tie no such stitches will inadvertently project from beneath the added strip.

- 5 By means of the present construction, the manufacturing procedure is greatly simplified because whatever loose stitches or threads may exist are disposed on the interior of the tie construction. For example, in Figure 2, in applying the stitches 10 21 or the stitches 23, no special precautions need be taken because the undersurface of the ply 17 is ultimately in a concealed position. The same applies to the construction of Figure 5.

Another advantage of the present mode of assembly arises from the desirability, under certain circumstances, to make a tie out of material that is cut on the bias. Inasmuch as the present additional reinforcement strip 20 is not so cut, but is cut "straight", the addition of this strip 20 to a tie which is cut on the bias imparts a desirable strengthening effect, minimizing undesirable longitudinal stretching that would otherwise take place.

It will be understood that changes in the details, herein described and illustrated for the purpose of explaining the nature of my invention, may be made by those skilled in the art without departing from the spirit and scope of the invention as expressed in the appended claims. It is, therefore, intended that these details be interpreted as illustrative, and not in a limiting sense.

Having thus described my invention, and illustrated its use, what I claim as new and desire to secure by Letters Patent is—

- 35 1. In an adjustable necktie, a neckband portion comprising inner and outer plies of tie material having their longitudinal edges turned inward and stitched together by concealed stitching, the inner ply having a series of perforations 40 arranged in predetermined longitudinally spaced relation, a reinforcement strip arranged on the outside of said inner ply and having perforations registering with those in said inner ply, and means marginally interengaging each pair of 45 registering perforations, said neckband portion being adapted to be doubled back upon itself and provided at its end with a male fastening element adapted to engage with a selected perforation, and said strip carrying indicia adjacent to 50 said perforations relevant to the adjustabilities in effective neckband length afforded by said perforations, respectively.

2. In an adjustable necktie, a neckband portion comprising inner and outer plies of tie ma-

terial having their longitudinal edges turned inward and stitched together by concealed stitching, the inner ply having a series of perforations arranged in predetermined longitudinally spaced relation, a reinforcement strip narrower than said inner ply and stitched along its edges to the outside of said ply, said strip having perforations registering with those in said inner ply, and means marginally interengaging each pair of registering perforations, said neckband portion being adapted to be doubled back upon itself and provided at its end with a male fastening element adapted to engage with a selected perforation, and said strip carrying indicia adjacent to said perforations relevant to the adjustabilities in effective neckband length afforded by said perforations, respectively.

3. In an adjustable necktie, the elements set forth in claim 1, in combination with a protective lining member between the inner and outer plies and at least coextensive with the perforated area of the neckband portion, so as to conceal said fastening element from the outside by two thicknesses of fabric.

4. In an adjustable necktie, a neckband portion comprising inner and outer plies of tie material having their longitudinal edges turned inward and stitched together by concealed stitching, the inner ply having a series of perforations arranged in predetermined longitudinally spaced relation, 30 a reinforcement strip coextensive in width with said inner ply and arranged on the outside of said inner ply with its longitudinal edges turned in and engaged by said stitching, said strip having perforations registering with those in said inner ply, and means marginally interengaging each pair of registering perforations, said neckband portion being adapted to be doubled back upon itself and provided at its end with a male fastening element adapted to engage with a selected perforation, and said strip carrying indicia adjacent to said perforations relevant to the adjustabilities in effective neckband length afforded by said perforations, respectively.

5. In an adjustable necktie, the elements set forth in claim 4, in combination with a protective lining member between the inner and outer plies and at least coextensive in length with the perforated area of the neckband portion, said lining member having its longitudinal edges secured by said stitching and serving, with the outer ply, to conceal said fastening element from the outside by two thicknesses of fabric.

WILLIAM MAYER.
